NO. 13,075
JULY 26, 1882

UNITED STATES PATENT OFFICE.

JAMES M. BRYCE, OF BEVERLY, NEW JERSEY.

DESIGN FOR A PRINTED FABRIC.

SPECIFICATION forming part of Design No. 13,075, dated July 25, 1862.

Application filed May 18, 1882. Term of patent 3½ years.

To all whom it may concern:

Be it known that I, JAMES M. BRYCE, of Beverly, in the county of Burlington and State of New Jersey, have invented a new and original Design for Printed Fabrics; and I do hereby declare that the following specification, taken in connection with the accompanying illustration, forming a part of the same, is a full, clear, and exact description thereof.

10 My design relates particularly to printed fabrics known as "calicoes," although it is equally applicable to silks, woolens, and other fabrics, either printed or woven.

15 It consists in the representation of animals in groups among flowering vines, as will hereinafter appear.

20 Referring to the illustration, A a represent respectively a full-grown and a baby elephant in a standing position. B B b represent two full-grown zebras and a young zebra respectively in a standing position. These groups

are separated from each other by a flowering vine, C, a portion, c, of the leaves of which differ in color from the others; but said leaves may be of the same color as the others, or may 25 be omitted. The groups of animals and the vine are repeated upon the surface or ground of the fabric to form the pattern.

The fabric may be produced in any preferred variety or combination of colors for obtaining 30 a desired effect.

What I claim, and desire to secure by Letters Patent, is—

The design for printed and other fabrics, consisting of animals in groups among flowering vines, substantially as described and 35 shown.

JAMES M. BRYCE.
